UNITED STATES PATENT OFFICE.

MARTIN WILLIAM BROWN, OF GALVESTON, TEXAS, ASSIGNOR TO ATLAS ENGINEERING WORKS, OF GALVESTON, TEXAS, A CORPORATION OF TEXAS.

DEVICE FOR TREATING EXHAUST GASES.

Application filed August 4, 1924. Serial No. 730,023.

To all whom it may concern:

Be it known that I, MARTIN WILLIAM BROWN, a citizen of the United States, residing at Galveston, in the county of Galveston and State of Texas, have invented certain new and useful Improvements in Devices for Treating Exhaust Gases; and I do hereby declare the following to be a full, clear, and exact description of the invention, such as will enable others skilled in the art to which it appertains to make and use the same.

The present invention relates to improvements in devices for treating exhaust gases, and has for an object to provide a device for use in connection with gasoline or other engines in which the exhaust gases are delivered directly on top of a body of water, causing the water to become agitated and heating the water so that vapor is formed. The vapor and agitated water extinguishes any sparks or fire that may be in the exhaust gases.

Another object of the invention consists in providing a device of this character in which the exhaust gases are baffled in such a way as to prevent the agitated water from being blown out of the device, and at the same time, trapping any sparks or fire that may be in the exhaust gases.

A further object of the invention lies in providing a casing for use with an internal combustion engine in which a body of water will be prevented from rising or shifting in the casing.

A still further object of the invention lies in providing a casing into which the exhaust gases are let out through a gauze strainer to act as an additional guard to extinguish sparks.

A still further object of the invention resides in providing an outlet chamber approximately in the center of the body of the casing, thereby insuring a uniform level of water at the point of outlet, and preventing the water from being blown out when ascending or descending hills or grades.

With the foregoing and other objects in view, the invention will be more fully described hereinafter, and will be more particularly pointed out in the claims appended hereto.

In the drawings, wherein like symbols refer to like or corresponding parts throughout the several views;

Figure 1 is a longitudinal section, with parts shown in elevation, of an improved device constructed according to the present invention.

Figure 2 is a longitudinal section taken on the line 2—2 of Figure 1.

Figure 3 is a perspective view of the exhaust pipe.

Figure 4 is a cross section taken on the line 4—4 in Figure 1, and

Figure 5 is a perspective view of one of the water check plates.

Referring more particularly to the drawings, 6 designates a substantially cylindrical casing of the device which may be made of sheet metal or other appropriate material, and 7 represents the exhaust pipe by which the exhaust gases from the engine are conveyed into the cylindrical space of the casing 6. The exhaust pipe 7 is mounted longitudinally within the upper central portion of the muffler casing, and is provided with a projecting threaded end 8, by which it may be attached to other sections of the exhaust pipe. The opposite end of the exhaust pipe 7 is closed, and the pipe is slotted longitudinally as indicated at 9, the slot being directed downwards so as to direct the exhaust gases at substantially right angles against the surface of a body of water or other liquid held in the casing 6. The water is let in through a filling neck 10, kept normally closed by the plug 11. The water may be poured to any suitable level, and the water is prevented from running from one end of the tank to the other by the motion of the vehicle because of the presence of the water check plates 12, which are substantially semi-circular and provided with the attaching flanges 13, by which the plates are riveted or otherwise secured within the lower portion of the casing 6. The plates are provided with a suitable number of perforations 14 in order to permit passage of the liquid from one side of the plates to the other, the plates forming compartments in the lower portion of the casing, and it is not intended to have the liquid body in separate compartments, but the body of liquid acts preferably as a whole, the plates, shown to be four in number, being merely located at spaced intervals within the liquid body to avoid the undue motion thereof incident to travel of the vehicle.

Baffle plates 15 and 16 are secured in the

casing 6 at the upper portion thereof and at opposite sides of the exhaust pipe 7, the pipes 15 and 16 being arranged diagonally and in downwardly convergent relation. 5 The lower ends of these baffle plates are spaced from the partitions or check plates 12, and the lower ends of the baffle plates do not intersect the line of the slot 9 in the exhaust pipe. In other words, they do 10 not interfere with the direct impingement of the exhaust products against the surface of the water body, but they act to prevent the water and exhaust gases from being blown out above the casing and they act 15 to trap any sparks and fire that may be in the exhaust gases.

At the center of the casing, above, and communicating with the same, is a chamber 17, just above the central part of the exhaust pipe, this chamber having the outlet pipe 18 for the exhaust gases after the same have been properly expanded and cooled in the muffler. A gauze strainer 19 is shown as depending from the chamber 17 25 and the outlet pipe 18, this strainer being cylindrical in form and closed at its bottom, and is of substantially less diameter than the diameter of the chamber so as to permit the enveloping by the cooled exhaust gases. The strainer will act as an additional guard to prevent the passing of sparks in case the water should become exhausted.

In the use of the device, the exhaust products enter through the pipe 7, issue downwardly through the slot 9, and impinge against the surface of the water between the two baffle plates 15 and 16. The water is agitated to a considerable extent, vapor is 35 formed, and the water and vapor effectually extinguish all sparks and cool the gases. The tendency will be for the water to be driven up to the opposite outer face of the baffle plates 15 and 16, and the water being 40 splashed up in these pockets, will be prevented from overflowing, and the only water that escapes will be that which is vaporized and passes out through the outlet pipe 18 with the other exhaust products. The 45 outlet chamber 17, being placed centrally of the casing 6, there will always be a uniform level of water at the central point, and this will always prevent the water from being blown out, particularly when the 50 water is at an inclination in the casing, due to the position of the vehicle on a grade.

It is obvious that various changes and modifications may be made in the details of construction and design of the above 55 specifically described embodiment of this invention without departing from the spirit thereof, such changes and modifications be-

ing restricted only by the scope of the following claims.

What is claimed is:

1. A device of the character described comprising a casing adapted to hold a body of liquid, an exhaust pipe having an opening to direct the exhaust products downwardly against the surface of the body of liquid, baffle plates at the sides of the exhaust pipe and forming pockets to catch the agitated water and gases, and an outlet for the gases after passing in contact with the liquid. 65

2. A device of the character described comprising a casing adapted to contain a body of liquid, a slotted exhaust pipe in the upper portion of the casing adapted to direct the exhaust products against the surface of the body of liquid, inclined baffle plates at opposite sides of said exhaust pipe, and an outlet chamber communicating with the central upper portion of said casing. 75

3. A device of the character described comprising a casing adapted to contain a body of liquid, a slotted exhaust pipe in the upper portion of said casing, inclined baffles at opposite sides of said exhaust pipe, an outlet chamber communicating with the upper central portion of said casing, and a strainer in said outlet chamber. 85

4. A device of the character described comprising a closed casing adapted to contain a body of liquid, means therein for avoiding the undue motion of liquid therein, baffle plates at opposite sides of said exhaust pipe, and an outlet chamber communicating with the upper intermediate portion of said casing. 95

5. A device of the character described comprising a closed casing, means for introducing a body of liquid thereto, spaced, transversely extending perforated check plates mounted in the lower portion of said casing, an exhaust pipe extending into the upper portion of said casing for directing the exhaust against the surface of the liquid body, and an outlet at substantially the central portion of said casing. 105

6. A device of the character described comprising a closed casing, means for introducing a body of liquid to the casing, perforated check plates mounted transversely at intervals in said casing, a slotted exhaust pipe for directing the exhaust products downwardly against the surface of the liquid, an outlet chamber communicating with the central upper portion of said casing and a gauze strainer of small diameter in said chamber adapted to be enveloped by the products therein. 115

MARTIN WILLIAM BROWN.
